CLAIM

We claim the ornamental design for handle for holding a sampling sponge, as shown and described.

DESCRIPTION

FIG. 1 is a perspective view of an embodiment of our ornamental design of the handle for holding a sampling sponge; FIG. 2 is a front view of the handle for holding a sampling sponge of FIG. 1;

FIG. 3 is a right side view of the handle for holding a sampling sponge of FIG. 1;

FIG. 4 is a left side view of the handle for holding a sampling sponge of FIG. 1;

FIG. 5 is a rear view of the handle for holding a sampling sponge of FIG. 1;

FIG. 6 is a top plan view of the handle for holding a sampling sponge of FIG. 1;

FIG. 7 is a bottom plan view of the handle for holding a sampling sponge of FIG. 1; and,

FIG. 8 is a perspective view of the handle for holding a sampling sponge of FIG. 1 but shown in an alternate position.
